UNITED STATES PATENT OFFICE.

WILLIAM M. STUMP, OF TALENT, OREGON.

CLAMPING DEVICE.

1,248,199.

Specification of Letters Patent. Patented Nov. 27, 1917.

Application filed December 23, 1916. Serial No. 138,658.

To all whom it may concern:

Be it known that I, WILLIAM M. STUMP, a citizen of the United States, residing at Talent, in the county of Jackson and State 5 of Oregon, have invented certain new and useful Improvements in Clamping Devices; and I do hereby declare the following to be a full, clear, and exact description of the invention, such as will enable others skilled 10 in the art to which it appertains to make and use the same.

My invention relates to new and useful improvements in clamping devices, and one that can be used for various purposes, such 15 as suspending objects or ornaments from walls, or in connection with cables, rods, or other devices where adjustments are to be made, and my object is to provide a supporting rod, by means of which the clamping 20 mechanism may be suspended from a wall, or other suitable point, and mount thereon a frame to which are pivotally attached clamping dogs for engagement with the supporting rod.

25 A further object is to provide means for causing a suspended object to operate the clamping dogs, whereby the supporting rod will be gripped and the frame held in adjusted position on the supporting rod.

30 A further object is to provide means for readily elevating or lowering the frame upon the supporting rod.

And a further object is to provide means for causing the clamping dogs to readily 35 grip the supporting rods.

Other objects and advantages will be hereinafter set forth and more particularly pointed out in the accompanying specification.

40 In the accompanying drawings which are made a part of this application,

Figure 1 is a front elevation of the clamp showing parts thereof broken away.

Fig. 2 is an edge elevation thereof,

45 Fig. 3 is a rear elevation of the clamp, and

Fig. 4 is horizontal sectional view through the clamping dogs and their pivotal connections, showing a slightly modified form of 50 the clamping dogs.

Referring to the drawings in which similar reference numerals designate corresponding parts throughout the several views, 1 indicates a supporting rod, the upper end 55 of which is preferably formed into an eye 2 which may be engaged with a hook, or

other object, to suspend the supporting rod, the lower end of the supporting rod being extended through a cross head 3 and attached thereto in any suitable manner, as 60 by means of nuts 4.

Slidably mounted upon the rod 1 is a frame 5, said frame having a transverse cavity 6 in which are pivotally mounted the inner ends of clamping dogs 7, said inner 65 ends having serrated cam faces 8 which are adapted to engage the supporting rod 1 and hold the frame from descending upon the supporting rod so long as the serrated edges of the cam faces are gripped into engagement with the supporting rod. The cam faces of the clamping dogs are brought into positive engagement with the supporting rod 1 by providing a strap 9, to which are pivoted links 10, the opposite ends of the 70 links being in turn pivotally attached to the outer ends of the clamping dogs 7, whereby when a downward pull is given to the strap 9, the cam faces of the clamping dogs will be forced into engagement with the supporting rod. 75

The lower end of the strap 9 has attached thereto a suspension rod 11 to which the object to be suspended is attached, the weight of the object pulling downwardly upon the 80 strap 9 serving to hold the cam faces of the clamping dogs into engagement with the supporting rod with sufficient force to hold the frame 5 against movement on the rod, the strap 9 being held in alinement with the supporting rod 1 and frame 5 by providing a lateral extension 12 in the strap 9 at a point above the pivotal connection with the links 10 with the strap, the remaining portion of the strap extending along the 85 rear face of the frame to a point beyond the upper end thereof, the extreme upper end of the strap having a right angular extension 13, the extensions 12 and 13 having registering bores through which the supporting rod 1 extends, thereby holding the strap in perfect alinement with the rod 1 at 90 all times.

In order to readily move the frame upwardly or downwardly upon the supporting 95 rod without removing the object which is supported by the suspension rod 11, an adjusting rod 14 is attached to the rear of the frame 5 through the medium of a clip 15, and by pushing or pulling upon the 100 adjusting rod 14 the frame and parts carried thereby may be readily moved up-

wardly or downwardly on the supporting rod, the downward movement of the adjusting rod causing the frame 5 to descend a sufficient distance independently of the 5 strap 9 to release the cam faces 8 from the supporting rod, and as soon as the downward pull on the adjusting rod 14 is released, the frame 5 is again moved slightly upward independently of the strap 9 by 10 means of a spring 16 surrounding the supporting rod 1 between the annular extension 12 and the lower end of the frame 5. The lower ends of the rods 11 and 14 are introduced through the respective ends of 15 the cross head 3, thereby retaining said rods in alinement with the supporting rod 1.

In operation, the upper end of the supporting rod 1 is anchored to a wall, or other suitable object and a picture, or other ornament, attached to the lower end of the suspension rod 11, when the adjusting rod 14 is operated to raise the picture to the proper elevation, and when so adjusted, the rod 14 is released, whereupon the weight of the 20 picture will instantly move the cam faces 8 of the clamping dogs into engagement with the supporting rod and thus hold the picture in its adjusted position.

If it is desired at any time to raise the 25 picture to a higher elevation, the adjusting rod 14 is grasped and moved upwardly, and if it is desired to lower the picture, a downward pull is given the adjusting rod, which will result in releasing the cam faces 30 from the supporting rod, thus permitting the frame and parts carried thereby to descend, and upon releasing the pull upon the adjusting rod, the spring 16 will act to cause the cam faces to immediately grip the 35 supporting rod and prevent further descent of the same.

Instead of using the device for supporting objects, the same may be employed for securing together the ends of cables or 40 attached to rods, and in fact may be used in any suitable manner as may be desired and for which the same is applicable.

In Fig. 4 will be seen a slightly modified 45 form of construction of the jaws of the 50 clamping dogs 7. In this instance, each of

the serrated faces 8 are grooved and partially embrace the rod 1 in order that a more effective bite may be had therewith.

I claim:

1. In a clamp, the combination with a 55 supporting rod, of a frame slidable on said rod, a pair of clamping dogs pivotally mounted in said frame, the inner end of the clamping dogs having cam faces adapted to interlock with the supporting rod, 60 a strap having right angular extensions through which said supporting rod extends, said frame being mounted between said extensions, links pivoted at one end to said strap and at their opposite ends to the 65 outer ends of said clamping dogs, a suspension rod carried by said strap adapted to interlock the cam faces with the supporting rod when an object is placed upon the suspension rod, and an adjusting rod attached 70 to the frame adapted to be operated to raise or lower the frame upon the supporting rod.

2. In a clamp, the combination with a 75 frame, of a pair of clamping dogs pivotally mounted to the frame, said clamping dogs having cam faces at their inner ends adapted to engage an object introduced through the frame and between the ends of the clamping dogs, a strap independently movable of the frame, links connecting said 80 strap to the outer ends of the clamping dogs, whereby when a downward pull is given to the strap, the cam faces of the locking dogs will be caused to grip the object between 85 the clamping dogs, means to manually move the frame independently of said strap whereby the dogs will be released from the object being gripped, and a spring between the frame and parts of the strap to move the frame independently of the strap and 90 reengage the clamping dogs with the object therebetween.

In testimony whereof I have signed my name to this specification in the presence of two subscribing witnesses.

WILLIAM M. STUMP.
